US0D1083874S

(12) **United States Design Patent** (10) **Patent No.:** **US D1,083,874 S**
(45) **Date of Patent:** ** *Jul. 15, 2025

(54) **HEADPHONE AND STAND ASSEMBLY**

(71) Applicant: **Guangzhou Minyuxing Technology Co., Ltd.**, Guangzhou (CN)

(72) Inventor: **Shumao Yuan**, Changning (CN)

(73) Assignee: **Guangzhou Minyuxing Technology Co., Ltd.**, Guangzhou (CN)

(*) Notice: This patent is subject to a terminal disclaimer.

(**) Term: **15 Years**

(21) Appl. No.: **29/853,998**

(22) Filed: **Sep. 21, 2022**

(51) LOC (15) Cl. **14-01**

(57) **CLAIM**

The ornamental design for a headphone and stand assembly, as shown and described.

DESCRIPTION

FIG. 1 is a front perspective view of the headphone component of the headphone and stand assembly, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the stand component of the headphone and stand assembly;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a front perspective view of the headphone and stand assembly.

The broken lines in the drawings illustrate the portions of the headphone and stand assembly, which form no part of the claimed design.

The unshaded surface adjacent the broken line edge in FIG. 4 forms no part of the claimed design.

1 Claim, 15 Drawing Sheets
